UNITED STATES PATENT OFFICE.

RUSSELL H. PARKER, OF BENTON COUNTY, OREGON.

IGNITION-CIRCUIT SWITCH.

Application filed February 21, 1925. Serial No. 10,891.

To all whom it may concern:

Be it known that I, RUSSELL H. PARKER, a citizen of the United States, residing in the county of Benton and State of Oregon, **5** have invented certain new and useful Improvements in Ignition-Circuit Switches, of which the following is a specification, reference being had to the accompanying drawings.

10 This invention relates to ignition circuit switches and more particularly to a combination switch.

An important object of the invention is to improve the switch disclosed in my prior **15** application, No. 672,922, filed November 5, 1923, for ignition circuit switches.

An important object of the invention is to provide a device of this character wherein any attempt to start the car prior to a **20** proper setting of the combination of the switch will result in the sounding of an alarm or signal.

A further object of the invention is to provide in a construction of this character **25** an arrangement such that the warning signal of the vehicle may be employed in the capacity of an alarm.

A still further object of the invention is to provide a device of this character **30** being of novel and improved form of combination switch.

A further and more specific object of the invention is the provision of a combination switch of this character including a switching part and contacts coacting therewith and arranged in pairs, the switching part being so constructed that in each alignment of one of its pairs of contacts, a circuit is established while a circuit is only established **35** through the other pair of contacts when the arms are in one certain position with relation thereto.

These and other objects I attain by the construction shown in the accompanying **45** drawings, wherein for the purpose of illustration is shown a preferred embodiment of my invention and wherein:—

Figure 1 is a perspective view of a switch constructed in accordance with my invention; **50**

Figure 2 is a vertical sectional view therethrough;

Figure 3 is a combined perspective of a dial and switching element removed;

Figure 4 is a detailed sectional view taken **55** through the switch showing the arrangement of the contacts and the operation of the switching elements, one of these switching elements being shown in the position in dotted lines where it aligns with the **60** ignition circuit completing contacts but does not connect the same; and

Figure 5 is a diagrammatic view showing the connections preferably employed **65** with a switch of the character shown.

Referring now more particularly to the drawings, the switch includes a casing 10 and a dial plate 11 having a plurality of dials 12 associated therewith. The casing **70** 10 has an outstanding flange about its upper edges, as indicated at 13, and the dial plate has a body 14 fitting into the upper end of and closing the casing, this body having an outstanding flange 15 resting against the flange 13 of the casing and held in engagement therewith by securing elements **75** 16 rendering the dial plate 11 unremovable from the casing. Embedded within the dial plate are a pair of longitudinally extending bars 17 and 18 arranged upon opposite sides **80** of the longitudinal center of the dial plate. Intermediate the dial plate and aligned with the longitudinal axis are a series of contact elements 19, 20, 21 and 22. Between adjacent contacts 19 to 22 are mounted pivots **85** 23.

The outer face of the dial plate 11 is formed with circular recesses 24 corresponding in number and arrangement and axial to the pivots 23. Each of these recesses exposes a portion of the longitudinally extending bars 17 and 18 and a pair of adjacent contact elements 19, 20, 21 and 22 for example, one recess exposes the contact 19 and the adjacent end of the contact 20, the next recess exposes the adjacent ends of the contacts 20 and 21 while the final recess exposes the contact 22 and the adjacent end of the contact 21. The contacts 19, 20, 21 and 22 are so arranged that they are differently spaced from the pivot openings 23 arranged therebetween, for example, the contact 19 is more nearly adjacent the pivot 23 between it and the contact 20 than the adjacent end of the contact 20. The contact 21 is more nearly adjacent the pivot opening between it and the contact 20 than the contact 20 and the contact 22 is more nearly adjacent the pivot opening between it and

the contact 21 than the contact 21. Each of the contacts 19 to 22 is further spaced from the pivot openings than the adjacent edges of the longitudinally extending bars 17 and 18. Directed through each opening 23 from the inner face of the dial plate and having its head arranged inwardly of the dial plate is a headed securing element 25. On the outer ends of these securing elements which 10 form pivots are secured dials 12. Each dial has a portion 27 rotatably fitting into the associated recess 24, a knob 28 by means of which it may be turned and a flange 29 overlying the face of a dial plate at the edges 15 of the recess 24. The outer face of each dial is provided with indicia 30 adapted to be associated with an indicating point 31 formed upon the dial plate face. These indicia and indicator points are preferably 20 of illuminous material so that the action of the dials may be observed in darkness as well as by day. Each dial has formed in its under surface a plurality of circularly arranged openings 32 adapted to interchangeably receive a pair of pins 33, these pins preferably diametrically arranged are adapted to extend through the body portion 34 of a switching element. This body portion has a further central opening 35 for 25 the passage of the pivot 25. The pins 33 being interchangeable in the openings provide a means for adjusting the body of the switching element about the dial so that it will take a position with relation to the dial 30 corresponding to a desired indicia 30 of the dial.

The body 34 of the switching element and in fact the entire switching element is 40 formed from resilient material such as spring brass, copper or bronze and has projecting from opposite sides thereof arms 36 and 37 being hereinafter referred to as the short and long arms of the switching element. The short arm is of sufficient length 45 to make contact with the contact elements 19, 20, 21 or 22 which is adjacent to but most remote from the pivot about which the switching element rotates and of sufficient length to engage the contact which is most 50 nearly adjacent while the long arm 37 is of sufficient length to engage the most remote contact when aligned therewith. The short arm 36 is, however, of sufficient length to engage either of the bars 17 or 18 when 55 moved out of alignment with the series of contacts 10 to 22 and the long arm will, of course, make such contact. It will be seen that by the above construction, the switching element will only make a connection 60 between adjacent contacts of the series 19 to 22 when one position of the associated dial is had and that in all other positions thereof a contact is established between the bars 17 and 18. When all of the dials are 65 arranged in their proper positions, a cir-

cuit is established from the contact 19 to the contact 22 but when any of the dials is not in its proper position, a circuit is established between the bars 17 and 18.

In the use of the device, the casing 10 is intended to enclose a necessary portion of the ignition circuit preferably the ignition coil, as indicated. This coil will have its input terminal, as more clearly shown in the diagrammatic view of Figure 5 connected to 70 the contact 19 and its output terminal connected to the interrupter of the circuit while the high tension terminal of the coil will be connected in its usual manner to the distributor proper. The battery B of the circuit is connected to the terminal 22 and to one terminal of the starter switch as shown. The second terminal of the starter switch is connected to the contact strip 18 and the horn of the vehicle is connected to the contact strip 17. With connections as above described, until the dials are all properly arranged, it is impossible to complete a circuit through the coil to provide the necessary 80 high tension current for operation of a motor. Furthermore, it will be obvious that when the starter switch is closed, a circuit will be established to the horn with the result that the same will be operated until all of the 85 dials are properly arranged or until the foot is released from the starter. Further attention is directed to the fact that the only means provided for cutting off the ignition circuit is the dials 12 and accordingly if the operator of the vehicle stops his engine, at 90 least one of these dials must be shifted from its circuit closing position, thus locking the combination. Since the operator's attention will be directed to the dials in shifting one of 95 these dials, in all probability he would shift all of the dials before leaving the machine whereas if the circuit could be destroyed by an ignition switch, it would be very possible that the operator would cut off the engine by 100 use of this switch and forget to shift the positions of any of the dials so that if the ignition switch was closed, the circuit would 105 again be properly completed.

It will of course be understood that the 110 particular shape or arrangement of the plate 11 is a matter of choice and the present illustration is but one of many forms which this plate may assume. It will also be understood that the casing will be provided with the usual terminal lugs 40 for making the 115 necessary connections to the switch. In addition to this, the coil box or casing 10 is preferably so formed that the recessed lug 41 of the coil may project through an opening 42 formed in one end of this casing so that 120 ready access may be had thereto in making the high tension connections to the switch.

Since the structure hereinbefore set forth 125 is obviously capable of certain modifications without materially departing from the spirit 130

of my invention, I do not limit myself to such specific structure except as hereinafter claimed.

I claim:—

5 1. In a switch, a plurality of contact elements arranged in pairs, a switch element for connecting the contacts of the pairs and alignable in either of two positions, each pair of contacts connecting the contacts of one 10 of said pairs at each alignment therewith and the contacts of the other pair only upon a predetermined alignment therewith.

15 2. In a switch, two pairs of contact elements, a rotating element for connecting said pairs of contacts and connecting one pair of contacts at all times when it is not in alignment with the other pair of contacts, said other pair of contacts being unequally spaced from the pivot of the connecting 20 member, said connecting member having arms for coaction with said contacts of unequal length, the shorter of said arms being of insufficient length to make contact with

the contact of said other pair most remote from said pivot.

3. In a switch, a pivot switching element embodying oppositely directed arms, a pair of contacts associated therewith and spaced apart a distance equal to the distance between opposite ends of the arms, said contacts being arranged upon opposite sides of the pivot of said switching element and being differently spaced from said pivot whereby the switching element when aligned with such contacts in one position thereof connects the contacts and in the opposite position thereof fails to connect the same, and a second pair of contacts associated with said switching element and with which the arms of the switching element make contact at all 40 times when the arms of the switching element are not aligned with the first named contacts.

In testimony whereof I hereunto affix my signature.

RUSSELL H. PARKER.
